WHEEL LOCKING CLAMP OR THE LIKE

Robert D. Henderson, Cincinnati, Ohio

Application September 29, 1950, Serial No. 12,390

Term of patent 14 years

(Cl. D54—2)

To all whom it may concern:

Be it known that I, Robert D. Henderson, a citizen of the United States, residing at Cincinnati, county of Hamilton and State of Ohio, have invented a new, original, and ornamental Design for a Wheel Locking Clamp or the like, of which the following is a specification, reference being had to the accompanying drawing, forming part thereof.

Fig. 1 is a top plan view of a wheel locking clamp showing my new design.

Fig. 2 is a side plan view of the device of Fig. 1.

In both figures a portion of the chain is shown by broken lines for convenience of illustration.

I claim:

The ornamental design for a wheel locking clamp or the like, as shown.

ROBERT D. HENDERSON.
